UNITED STATES PATENT OFFICE.

GEORGE W. MAXWELL, OF LOS ANGELES, CALIFORNIA.

MECHANICAL DIRECTORY.

SPECIFICATION forming part of Letters Patent No. 697,378, dated April 8, 1902.

Application filed October 23, 1900. Serial No. 34,079. (No model.)

To all whom it may concern:

Be it known that I, GEORGE WASHINGTON MAXWELL, a citizen of the United States, residing at Los Angeles, in the county of Los Angeles and State of California, have invented new and useful Improvements in Mechanical Directories, of which the following is a specification.

This invention relates to a mechanical directory of the type heretofore invented by me and set forth in certain applications for patents which I have filed in the United States Patent Office as follows: Serial No. 676,132, filed April 1, 1898, renewed August 1, 1900, Serial No. 25,591; Serial No. 684,712, filed June 29, 1898, renewed August 1, 1900, Serial No. 25,592; Serial No. 705,446, filed February 13, 1899, and Serial No. 737,688, filed November 20, 1899, and in which applications I have shown and described a directory comprising the combination of two rollers; a strip fastened at its ends to said rollers, respectively, to be wound and unwound from roller to roller; means for driving one of said rollers; means for driving the other of said rollers; a prime mover adapted to be moved in one and the other direction, and automatic reversing mechanism operated by the prime mover and interposed between said prime mover and the means for driving said rollers to operate the one of said means to drive one of said rollers and to release the other of said rollers when the prime mover is turned in one direction and to operate the other means to drive the other roller and to release the first-named means and roller when the prime mover is turned in the other direction.

In my application Serial No. 737,688, filed November 20, 1899, I have described and claimed the combination of a plurality of pairs of rollers; a plurality of strips fastened at their opposite ends to the rollers of said pairs respectively to be wound and unwound from roller to roller of their respective pairs, means operatively connected with one roller of each of said pairs to cause said rollers to simultaneously rotate, means operatively connected with the other roller of each of said pairs to cause said other rollers to simultaneously rotate, a reversible prime mover, and automatic-shifting power-transmitting mechanism interposed between said

prime mover and said roller-rotating means to drive the one and release the other of said roller-rotating means when the prime mover is operated in the one direction and vice versa when the prime mover is operated in the other direction. I have also shown and claimed the combination, with said mechanism, of a supplemental directory-strip and an index, and for that reason said inventions are not broadly claimed herein.

An object of my present invention is to produce a mechanical directory which will run lighter and more perfectly and practically without any noise.

My present invention relates to improvements whereby the use of cog-wheels is dispensed with, and the invention is operated by sprocket chains and wheels; also, to improvements whereby the index is cheapened, simplified, and reduced in size and diminished in speed. It also relates to novel means for the automatic reversal of the directory-strip.

It is to be understood that in carrying out parts of my present invention I am not limited to the use of sprocket chains and wheels; but I prefer such use and have therefore illustrated the invention only as applied with sprocket chains and wheels.

My present invention embraces the various parts and combinations for operating the directory-strips and also embraces the novel indexing appliance shown, whereby the exhibition of the printed matter on the rapidly-moving directory-strips will be indicated by the exhibition in succession of appropriate characters on a slowly-moving index-strip.

The accompanying drawings illustrate my invention.

Figure I is a fragmental perspective view of my invention, parts being broken away for clearness of illustration. Fig. II is a front elevation of the means for driving the rollers and for automatically reversing the movement of the directory-strips. Portions of the sprocket-chains are broken away for clearness of illustration. Fig. III is a sectional elevation on line III III, Fig. IV, looking to the left. Portions of the frame or support are broken to expose the rollers and ribbons. Fig. IV is a front elevation of my newly-invented mechanical directory. Portions of the

case are broken for clearness of illustration. Fig. V is a horizontal sectional detail of the prime-mover shaft and a fragment of the master sprocket-wheel. Line V V, Fig. II, 5 indicates the line of section.

40 indicates in a general way a frame or support for the mechanism, and 50 a motor. *a a'* indicate a pair of rollers. *b b'* indicate another pair of rollers.

10 *c* indicates a directory-strip fastened at its ends, respectively, to the rollers *a a'*.

d indicates a directory-strip fastened at its ends, respectively, to the rollers *b b'* of the other pair. Suitable means operatively connect one roller *a* of the one pair with the one roller *b* of the other pair to cause their simultaneous operation. Such means preferably consist of a sprocket-chain *e*, a sprocket-wheel 1 for the roller *a*, and a sprocket-wheel 2 for 15 the roller *b*.

20 Like means *e' 1' 2'* operatively connect the other roller *a'* of the one pair with the other roller *b'* of the other pair for their simultaneous operation. Suitable means are provided for driving one of said first-named

25 connected rollers *a b*.

f indicates a roller-driving sprocket-wheel constituting the means for driving the roller *a*, and *g* indicates a clutch for connecting said roller-driving means *f* with and disconnecting it from said roller *a*. *f'* indicates like roller-driving means for driving one of said second-named connected rollers. A clutch *g'* is provided for connecting said roller-driving means *f'* with and disconnecting it from said other roller *a'*. In the drawings the roller-driving means *f* and *f'* are on the rollers *a a'*, respectively. *h* indicates a master-wheel operatively connected with both of said roller-driving means for simultaneously driving them. When sprocket-wheels are used, as shown at *f f'*, the master-wheel *h* is also a sprocket-wheel and is connected with said sprocket-wheels *f f'* by means of the sprocket-chain *i*. Suitable means are 35 supplied for rotating the master-wheel in one and the other direction. For this purpose a suitable prime mover, such as the crank *j*, fastened to a shaft *k*, is arranged to turn said shaft, and the wheel *h* is mounted on said 40 shaft to have a limited rotation thereon.

m and *n* indicate pins on the shaft and wheel respectively arranged on one side of the master-wheel to engage with each other when the crank is turned in one direction to 45 cause the crank to turn the wheel before the crank makes a complete revolution in the one direction. *m' n'* indicate two like pins on the other side of the master-wheel, which will engage with each other to turn the master-wheel 50 *h* when the crank is turned in the other direction. Suitable means are operatively connected with said master-wheel *h* for simultaneously operating the clutch mechanisms *g g'* to throw the one into and the other out of 55 operation when the wheel is rotated in one direction and vice versa when the wheel is rotated in the other direction. Such means

as illustrated consist in a screw-threaded portion *o* on the shaft *k*, a nut *p* for the master-wheel *h*, screwed on the screw-threaded portion *o* to shift the master-wheel along the shaft as the shaft is turned in one and the other direction, a lever *q*, pivoted by a pivot *r* and furnished with two arms *s*, which stand, respectively, on the opposite sides of the master-wheel *h*, to be engaged thereby when the wheel shifts laterally, the other end of the lever *q* being connected through the roller-driving means *f* to operate the clutch *g*, connected therewith, to throw said clutch into and out of action, thus to connect and disconnect such roller-driving means *f* with and from the roller *a* when the wheel *h* is shifted in one and the other direction, respectively, and a like lever *q'*, pivoted by a pivot *r'* and arranged with 80 arms *s'*, which stand, respectively, on the opposite side of the wheel *h*, said lever *q'* being operatively connected through the other roller-driving means *f'* for operating the clutch *g'* to connect and disconnect said clutch, so that the reversal of the rotation of the prime mover will simultaneously throw the one clutch mechanism into and the other clutch mechanism out of operation.

When the crank *j* is turned in one direction, 95 the screw *o*, acting on the nut *p*, will shift the wheel *h* in one direction, thus throwing one clutch out and the other clutch into operation—thus, for instance, releasing one roller *a* and rotating the other roller *a'*—and a reverse movement of the crank causes the screw *o* to shift the wheel *h* in the other direction, thus disconnecting the other roller *a'* and connecting the roller *a*.

The directory-strips *c* and *d* are furnished 105 with systematically-arranged information 77, appropriately printed upon both sides of the strips, and the information contained therein will be exhibited through four openings *t t' t'' t'''*. *u* indicates idlers appropriately arranged for properly holding the directory-strips in position for exhibition through said openings.

v v' indicate index-strips connected by a cord or other flexible connection *w* with a spindle *x*, which is connected by the sprocket-wheel *y*, sprocket-chain *z*, and sprocket-wheel *y'* with one of the rollers *a*, so that the rotation of the roller will move the index-strip synchronously with the movement of the 120 directory-strip and in appropriate relation thereto. The index-strips are arranged on opposite sides of the front of the case 3 of the machine, and their index characters 4 are appropriately arranged to be separately exhibited through sight-openings 5 in said case 3, which constitutes a cover for all portions of said strips (not shown) through the sight-openings.

6 indicates a spring which may or may not 130 be supplied to return the index-strip to normal position. Such spring is not positively required, for the reason that the index-strip *v* will be a metal bar of sufficient weight to

descend by its own gravity and the flexible connection *w* will operate to lift the bar end-wise against the force of gravity when the machine is operated in one direction and allow it to descend when the machine is operated in the other direction.

The index-strips *b b'*, with their lettering, are housed within the case, and the lettering thereon is thus projected, and there are no projecting index-hands outside the case to be broken off.

In practical use the operator who desires to inspect a name and address of the directory will turn the crank *j* in one or the other direction to bring the required name into view. He will determine the direction in which the crank is to be turned by inspection of the directory-strip and index. He will turn the crank rapidly in the required direction and will watch the slowly-moving index until the appropriate character appears in the sight-opening of said index. Then he will turn the crank more slowly to allow him to inspect the names under the appropriate character on the directory-strip and will turn the crank until the required name is brought to view. When the crank has been turned in one direction and it is desired to turn the ribbon in the other direction, the crank will be reversed, and the screw-thread *o*, operating upon the nut *p*, will shift the member *h* along the shaft *k*, thus operating the levers *q q'* to simultaneously release one of the clutches and engage the other clutch, thus releasing the rollers at one end of the strips and operating the rollers at the other ends of the strips, thus reversing the movement of the ribbons or strips *c d*.

What I claim, and desire to secure by Letters Patent of the United States, is—

1. The combination of two pairs of rollers; a strip fastened at its ends respectively to the rollers of one pair; a strip fastened at its ends respectively to the rollers of the other pair; means operatively connecting one roller of one pair with one roller of the other pair for their simultaneous operation; means operatively connecting the other roller of one pair with the other roller of the other pair for their simultaneous operation; means for driving one of said first-named connected rollers; a clutch for connecting said means with and disconnecting it from said roller; means for driving one of said second-named connected rollers; a clutch for connecting said means with and disconnecting it from said last-named roller; a wheel operatively connected with both of said roller-driving means for simultaneously driving them; means for rotating said wheel in one and the other direction; and means operatively connected with said wheel for simultaneously operating the clutch mechanisms to throw the one into and the other out of operation when the wheel is rotated in one direction, and vice versa when the wheel is rotated in the other direction.

2. The combination of two pairs of rollers;

a strip fastened at its ends respectively to the rollers of one pair; a strip fastened at its ends respectively to the rollers of the other pair; means operatively connecting one roller of one pair with one roller of the other pair for their simultaneous operation; means operatively connecting the other roller of one pair with the other roller of the other pair for their simultaneous operation; means for driving one of said first-named connected rollers; a clutch for connecting said means with and disconnecting it from said rollers; means for driving one of said second-named connected rollers; a clutch for connecting said means with and disconnecting it from said last-named roller; a wheel operatively connected with both of said roller-driving means for simultaneously driving them; means for rotating said wheel in one and the other direction; means for shifting said wheel to one side when rotated in one direction and to the other side when rotated in the other direction; and means operatively connected with said shifting wheel to simultaneously connect the one clutch and disconnect the other clutch when the wheel is shifted to one side, and vice versa when the wheel is shifted to the other side.

3. The combination of two pairs of rollers; a strip fastened at its ends respectively to the rollers of one pair; a strip fastened at its ends respectively to the rollers of the other pair; means operatively connecting one roller of one pair with one roller of the other pair for their simultaneous operation; means operatively connecting the other roller of the one pair with the other roller of the other pair for their simultaneous operation; means for driving one of said first-named connected rollers; a clutch for connecting said means with and disconnecting it from its roller; means for driving one of said second-named connected rollers; a clutch for connecting said means with and disconnecting it from its roller; a wheel operatively connected with both of said roller-driving means for simultaneously driving them; means for rotating said wheel in one and the other direction; means for shifting said wheel to one side when rotated in one direction and to the other side when rotated in the other direction; and levers operatively connected with said shifting wheel to respectively operate the clutches to simultaneously connect the one clutch and disconnect the other clutch when the wheel is shifted to one side, and vice versa when the wheel is shifted to the other side.

4. The combination of two pairs of rollers; a strip fastened at its ends respectively to the rollers of one pair; a strip fastened at its ends respectively to the rollers of the other pair; means operatively connecting one roller of one pair with one roller of the other pair for their simultaneous operation; means operatively connecting the other roller of one pair with the other roller of the other pair for their simultaneous operation; means for driving one of said first-named connected rollers; a clutch for connecting said means with and disconnecting it from its roller; means for driving one of said second-named connected rollers; a clutch for connecting said means with and disconnecting it from its roller; a wheel operatively connected with both of said roller-driving means for simultaneously driving them; means for rotating said wheel in one and the other direction; and means operatively connected with said wheel for simultaneously operating the clutch mechanisms to throw the one into and the other out of operation when the wheel is rotated in one direction, and vice versa when the wheel is rotated in the other direction.

one of said first-named connected rollers; a clutch for connecting said means with and disconnecting it from said roller; means for driving one of said second-named connected rollers; a clutch for connecting said means with and disconnecting it from its roller; a shaft furnished with a screw-threaded portion; a wheel furnished with a nut mounted on said threaded portion and having a limited 5 rotation on said shaft; and means operatively connected with said wheel to respectively operate the clutches to simultaneously connect the one clutch and disconnect the other clutch when the wheel is shifted to one side, 10 and vice versa when the wheel is shifted to 15 the other side.

5. The combination of two pairs of rollers; a strip fastened at its ends respectively to the rollers of one pair; a strip fastened at its ends 20 respectively to the rollers of the other pair; means operatively connecting one roller of one pair with one roller of the other pair for their simultaneous operation; means operatively connecting the other roller of one pair 25 with the other roller of the other pair for their simultaneous operation; means for driving one of said first-named connected rollers; a clutch for connecting said means with and disconnecting it from said roller; means for 30 driving one of said second-named connected rollers; a clutch for connecting said means with and disconnecting it from said last-named roller; a laterally-shifting wheel for 35 operating said roller-driving means; and levers operatively connected with said shifting wheel to respectively operate the clutches to simultaneously connect the one clutch and disconnect the other clutch when the wheel is shifted to one side, and vice versa when the 40 wheel is shifted to the other side.

6. The combination of two pairs of rollers; a strip fastened at its ends respectively to the rollers of one pair; a strip fastened at its ends 45 respectively to the rollers of the other pair; sprocket-wheels fastened to the rollers respectively; a sprocket-chain connecting one sprocket-wheel of one pair with one sprocket-wheel of the other pair for their simultaneous operation; a sprocket-chain connecting the 50 other sprocket-wheel of the one pair with the other sprocket-wheel of the other pair for their simultaneous operation; a sprocket-wheel for driving one of said first-named connected rollers; a clutch for connecting said driving 55 sprocket-wheel with and disconnecting it from said roller; a sprocket-wheel for driving one of said second-named connected rollers; a clutch for connecting said last-named driving sprocket-wheel with and disconnecting it from 60 said last-named roller; a master sprocket-wheel; a sprocket-chain led around the master sprocket-wheel and the driving sprocket-wheels for their simultaneous operation; means for rotating the master sprocket-wheel 65 in one and the other direction; and means operatively connected with said master sprocket-wheel for simultaneously operating

the clutch mechanisms to throw the one into and the other out of operation when the wheel is rotated in one direction, and vice versa 70 when the wheel is rotated in the other direction.

7. The combination of two pairs of rollers; a strip fastened at its ends respectively to the rollers of one pair; a strip fastened at its ends 75 respectively to the rollers of the other pair; sprocket-wheels fastened to the rollers respectively; a sprocket-chain connecting one sprocket-wheel of one pair with one sprocket-wheel of the other pair for their simultaneous 80 operation; a sprocket-chain connecting the other sprocket-wheel of the one pair with the other sprocket-wheel of the other pair for their simultaneous operation; a sprocket-wheel for driving one of the first-named connected rollers; a clutch for connecting said driving 85 sprocket-wheel with and disconnecting it from said roller; a sprocket-wheel for driving one of the second-named connected rollers; a clutch for connecting said last-named driving sprocket-wheel with and disconnecting it from 90 said last-named roller; a master sprocket-wheel; a sprocket-chain led around the master sprocket-wheel and the roller-driving sprocket-wheels for their simultaneous 95 operation; means for rotating the master sprocket-wheel in one and the other direction; means for shifting said master-wheel to one side when rotated in one direction and to the other side when rotated in the other direction; and 100 means operatively connected with said master-wheel to respectively operate the clutches to simultaneously connect the one clutch and disconnect the other clutch when the wheel is shifted to one side, and vice versa when 105 the wheel is shifted to the other side.

8. The combination of two pairs of rollers; a strip fastened at its ends respectively to the rollers of one pair; a strip fastened at its ends 110 respectively to the rollers of the other pair; sprocket-wheels fastened to the rollers respectively; a sprocket-chain connecting one sprocket-wheel of one pair with one sprocket-wheel of the other pair for their simultaneous operation; a sprocket-chain connecting the 115 other sprocket-wheel of the one pair with the other sprocket-wheel of the other pair for their simultaneous operation; a sprocket-wheel for driving one of the first-named connected rollers; a clutch for connecting said sprocket-wheel with and disconnecting it from 120 said roller; a sprocket-wheel for driving one of the second-named connected rollers; a clutch for connecting said last-named sprocket-wheel with and disconnecting it from 125 said last-named roller; a master sprocket-wheel; a sprocket-chain led around the master sprocket-wheel and the roller-driving sprocket-wheels for their simultaneous 130 operation; means for rotating the master sprocket-wheel in one and the other direction; means for shifting the master-wheel to one and the other side at its rotations in one and the other direction, respectively; and

levers operatively connected with said master-wheel to respectively operate the clutches to simultaneously connect the one clutch and disconnect the other clutch when the wheel is shifted to one side, and vice versa when the wheel is shifted to the other side.

9. The combination of two pairs of rollers; a strip fastened at its ends respectively to the rollers of one pair; a strip fastened at its ends respectively to the rollers of the other pair; means operatively connecting a roller of one pair with a roller of the other pair to cause their simultaneous operation; means connecting the other roller of the one pair with the other roller of the other pair for their simultaneous operation; a shaft; means for operating the shaft in one and the other direction; means for transmitting motion from the shaft to one of the first-named connected rollers; means for transmitting motion from the shaft to one of the second-named connected rollers; clutches for respectively connecting said motion-transmitting means with their respective rollers and disconnecting them therefrom; and means operatively connected with the shaft for simultaneously operating said clutch-operating means to connect the one and disconnect the other when the shaft is turned in one direction, and vice versa when the shaft is turned in the other direction.

10. The combination of two pairs of rollers; a strip fastened at its ends respectively to the rollers of one pair; a strip fastened at its ends respectively to the rollers of the other pair; means operatively connecting a roller of one pair with a roller of the other pair; means operatively connecting the other roller of the one pair with the other roller of the other pair; roller-operating means for driving one of the first-named connected rollers; roller-operating means for driving one of the second-named connected rollers; a shaft furnished with a screw-thread and operatively connected to drive said roller-operating means; a clutch for connecting and disconnecting one of said roller-operating means with and from its roller; a clutch for connecting and disconnecting the other roller-operating means with and from its roller; means for rotating the shaft; and means actuated by the screw for simultaneously disconnecting one clutch and connecting the other clutch when the shaft is

turned in one direction, and vice versa when the shaft is turned in the other direction. 55

11. In a directory, the combination with the strip-operating means, of a shaft; a master-wheel having a limited lateral and rotary movement on said shaft; means connecting said wheel with the roller-operating means; two levers for throwing said roller-operating means into and out of operative position; and means for shifting said wheel in one direction to operate said levers to throw one of said roller-operating means into and the other of 65 said roller-operating means out of operative position when the wheel is shifted in one direction, and vice versa when the wheel is shifted in the other direction.

12. In a directory, a support; two sets of 70 rollers journaled therein; a directory-ribbon on each set of rollers; means for connecting the corresponding rollers of each set to rotate them in unison; clutch mechanism connected with both rollers of one set; a bifurcated lever for each clutch; a screw-threaded crank-shaft; and a screw-threaded master-wheel mounted on said shaft and having its periphery within the bifurcations of said levers, said wheel being operatively connected with said 75 set of rollers and adapted to be moved laterally upon its shaft when the direction of rotation of the shaft is reversed.

13. In a directory, a casing provided with four sight-openings; a master-wheel; two sets 85 of rollers journaled in said casing; means for driving said rollers from the master-wheel; a directory-ribbon on each set of rollers, each side of each ribbon being provided with names; means for exposing a portion of each 90 side of each ribbon through one or the other of said openings; and means for simultaneously moving said ribbons longitudinally in the same direction and automatically reversing the direction of their movement as the 95 direction of rotation of the master-wheel is reversed.

In witness whereof I have signed my name to this specification, in the presence of two subscribing witnesses, at Los Angeles, California, this 16th day of October, 1900. 100

GEO. W. MAXWELL.

Witnesses:

JAMES R. TOWNSEND,
JULIA TOWNSEND.
